UNITED STATES PATENT OFFICE.

JAMES F. CRAVEN, OF PITTSBURGH, PENNSYLVANIA, ASSIGNOR TO CRAVEN ENGINEERING COMPANY, OF PITTSBURGH, PENNSYLVANIA, A CORPORATION OF PENNSYLVANIA.

WAX PACKAGE OR CANDLE.

1,053,577.

Specification of Letters Patent. Patented Feb. 18, 1913.

Application filed November 17, 1911. Serial No. 880,929.

To all whom it may concern:

Be it known that I, JAMES F. CRAVEN, a resident of Pittsburgh, in the county of Allegheny and State of Pennsylvania, have 5 invented a new and useful Improvement in Wax Packages or Candles, of which the following is a specification.

This invention relates to packages of wax or other substance, and more particularly to 10 one which may be used as a candle.

The object of this invention is to provide a candle of wax or other like substance, so 15 put up that the form and shape thereof will not be affected by being stored in comparatively warm places or in comparatively warm weather, and which is self-extinguishing in use.

The invention comprises the construction and arrangement of parts hereinafter 20 described.

In the accompanying drawing Figure 1 is a longitudinal section through the container in the form in which it is transported and stored; Fig. 2 is an end view of the 25 same with one cap removed; and Fig. 3 illustrates the manner in which the container can be removed in sections.

The container is formed as a tube or casting 1 of any cheap substance or material, 30 but nevertheless having sufficient rigidity so that it will prevent distortion of the contents in warm weather or from other cause. Preferably the container is formed of paper or paste board. The contents are indicated 35 at 2 and, preferably, these are molded into the container by pouring or filling the same thereto when in a molten or liquid or semi-liquid form and then allowing the same to set or harden. The ends of the container 40 are closed, preferably by means of caps 3 and 4. As shown the cap 3, at the upper end of the package, is removable or detachable being formed preferably of paper or paste board in cup shape and having its 45 side wall or flange 5 snugly fitting the tube 1. The cap or head 4 is shown as a paper disk firmly secured to the end of the tube 1 as by crimping the tube and disk together or by gluing the disk in place. The caps 50 3 and 4 may, if desired, be formed of other inexpensive material and either one thereof may be removable from or securely fixed to the tube, as preferred. The substance when contained in this container is protected 55 against dirt, and the container also is of

such rigidity that the package can be stored indefinitely without danger of distortion of the contents. As a consequence, this device is well adapted for containing or forming paraffin or other wax or tallow candles and the like, which, as is well known, sag or warp out of shape and become crooked and otherwise deformed, when stored or preserved for any length of time in ordinary summer temperature.

In the form of candle shown in the drawings, a wick 6 is placed in the container before the contents are poured into the same, one end of the wick being preferably secured to the cap 4, as at 7, and the other end 60 thereof projecting above the top of the body of wax in the container. In using the candle 65 one of the heads or caps is removed and the wick lighted whereupon the device will burn until it burns down so low into the tubular 70 container that it is extinguished by the carbon dioxide which is formed and collects in the container. Consequently the device is well adapted for use as a candle in positions 75 where it is desired that the candle will extinguish itself at the end of a given time. The paper or pasteboard shell or covering is 80 from its nature infusible, and is treated, as are also the caps, with a substance which 85 renders it non-inflammable. Various preparations for rendering paper or fiber non-inflammable are well known, one such consisting in coating the surface with Bakelite and this will serve as a coating or impregnating substance for the paper tube. Also, 90 the paper tube may be made in such a manner that it can be removed in sections to permit the candle to be relighted after it has burned down for a certain distance. To 95 this end the tube preferably is formed in sections 8, these being loosely connected together, such as by perforating, creasing, or otherwise weakening the paper at intervals on annular lines, as indicated at 9. Consequently when the candle has burned down 100 fairly deep into the tube the upper portion of the tube can be torn off or otherwise removed as shown in Fig. 3, and as the candle burns away the tube is removed in successive sections until the entire candle is consumed. The cap 3, however, fits any section 105 of the cylindrical tube and may be used as a cover until the entire package is consumed, and in the case of the candle as an extinguisher therefor.

In its most specific form the invention comprises a candle made of wax, tallow or similar substance and having a wick molded into a rigid non-inflammable container so formed that it can be removed in sections and which container can be closed or covered, thus forming an original package with the candle contained therein and which serves as a means to preserve the candle from distortion or deterioration or from sticking to others and keeps the same clean, and which in use serves as a holder for the candle and also as an extinguisher for the candle when the same has burned down into it.

15 The container may be used to hold wax, tallow, paraffin or other like substances in the form of a candle as stated. It is of course also adapted to contain the same substances, without a wick, in cases where it is desired to keep a supply of these materials on hand for occasional use at intervals under which circumstances the sectional container may be removed piecemeal and as much of the contents exposed for cutting or 25 shaving as desired, the cap or cover at all times serving as a means for keeping the contents clean and aseptic.

What I claim is:—

1. A candle comprising an outer shell or covering formed of infusible and non-inflammable material and inclosing a body of wax or other combustible substance, and a wick therein, said body being adapted to be consumed in burning of the candle and to

have its upper surface lower in said shell, 35 and said shell forming a chamber above the candle body to receive and retain the products of combustion, thereby causing the candle to extinguish itself after burning for a limited time, and said shell having a number of weakened portions to permit removal of sections of the shell to expose additional portions of the combustible material.

2. A candle comprising an outer shell or covering formed of infusible and non-inflammable material and inclosing a body of wax or other combustible substance, and a wick therein, said body being adapted to be consumed in burning of the candle and to have its upper surface lower in said shell, 45 and said shell forming a chamber above the candle body to receive and retain the products of combustion, thereby causing the candle to extinguish itself after burning for a limited time, and said shell having a 50 number of weakened portions to permit removal of sections of the shell to expose additional portions of the combustible material, and a cap formed to fit the shell at any 55 of the weakened portions and adapted to be used as an extinguisher.

In testimony whereof, I have hereunto set my hand.

JAMES F. CRAVEN.
